(57) **CLAIM**

The ornamental design for a digital camera, as shown and described.

DESCRIPTION

FIG. 1 is a top, front and right side perspective view of a digital camera showing my new design;

FIG. 2 is a front elevational view thereof;

FIG. 3 is a top plan view thereof; and,

FIG. 4 is left side elevational view thereof.

The features shown in broken lines in the drawings depict environmental subject matter only and form no part of the claimed design.
